L.L.C.(57) **CLAIM**

The ornamental design for a clamp with light, as shown and described.

DESCRIPTION

FIG. 1 is a front perspective view of the clamp with light, showing my new design;

FIG. 2 is a right side elevational thereof;

FIG. 3 is a left side elevational view thereof;

FIG. 4 is a rear elevational view thereof;

FIG. 5 is a front elevational view thereof;

FIG. 6 is a bottom plan view thereof; and,

FIG. 7 is a top plan view thereof.

The broken lines shown in the figures are for the purpose of illustrating portions of the clamp with light and form no part of the claimed design.
